I. E. SMITH

OIL BURNER INSTALLATION

Filed May 25, 1926

Fig. 1

INVENTOR

Ira E. Smith

BY *Henry J. Weidner* ATTORNEY

UNITED STATES PATENT OFFICE.

IRA E. SMITH, OF STOCKTON, CALIFORNIA.

OIL-BURNER INSTALLATION.

Application filed May 25, 1926. Serial No. 111,621.

This invention relates to improvements in means for mounting electrically driven oil burners in connection with the furnace or firebox in which the burner is located.

Such an oil burner structure includes the burner in the firebox, as above stated, a motor outside the firebox, and driving connections between the burner and the motor. Owing to such connections the burner and motor must be rigidly connected together. These members therefore are usually mounted on a common rigid base which is partly supported by some portion or other of the furnace. The operation of the motor sets up an unavoidable vibration and humming noise which, by reason of the contact of the base with the furnace, is transmitted to and intensified by the metal of the furnace and is carried thence through all the piping leading from the furnace. The result is that when an installation of this character is made the vibration and noise of the motor are very noticeable all over the building, especially if the apparatus is set up in an ordinary frame residence.

The principal object of my invention therefore is to eliminate the above objectionable features by mounting the burner in such a manner that neither it nor the base contacts with any portion of the furnace, and without interfering with the necessary rigidity of installation.

A further object of the invention is to provide a cover for the externally located parts of the burner structure, so as to protect the same and to form a substantially air-tight enclosure about the firebox door so that air for the burner must pass to the burner through an opening provided in the cover enclosure. This permits of more accurate control of the air than is possible if the usual opening and firebox door are used as the air intake and damper means, since owing to the necessary members projecting to the burner through said opening, it is not easy to mount a door therefor so as to have the desired movement and accurate air controlling features.

Another object of the invention is to construct this covering of such material that while closely surrounding and attached to the firebox door, said covering will not burn nor will it impart any vibration from the motor to the furnace.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved oil burner installation shown in connection with a firebox.

Fig. 2 is a perspective view of the cover for the external parts of the burner structure detached from said structure and firebox.

Referring now more particularly to the characters of reference on the drawings, the numeral 1 denotes the firebox of the furnace having the usual side opening 2. Mounted on the floor outside the furnace is a rigid base 3. Projecting from the end of the base adjacent the firebox and formed integral therewith or rigidly secured thereto in any suitable manner is a rigid extension 4. This extension is clear of the floor and projects into the furnace through the opening 2 in spaced relation to the sides and bottom thereof. Supports 5 project upwardly from the inner end of the extension and support a burner 6 of suitable form, such as for instance as is shown in my Patent No. 1,582,552 dated April 27th, 1926, though other forms of burner may of course be mounted instead of the one shown. The general arrangement of the motor, burner and co-related parts is substantially as shown in my Patent No. 1,512,247 dated October 21st, 1924.

The base 3 supports a driving motor 7 for the burner, said motor being operatively connected to the rotating parts of the burner by a horizontal shaft 8 which extends from the motor to the burner through the opening 2.

By reason of this arrangement it will be seen that none of the vibration or noise of the motor is transmitted direct to the furnace, especially if the floor on which the base is mounted is of concrete, as is usually the case.

In connection with this arrangement, I

provide a cover for the external parts of the burner structure, so as not only to protect the motor and other accessories mounted on the base from harm, but to enable the air for the burner to be accurately controlled.

This cover structure includes a rigid panel member 9 mounted on and projecting upwardly from the base at the outer end thereof. This panel has a large opening 10 with a cooperating damper or door 11 which may be manipulated to control the admission of air through the opening by any suitable means. Extending from the sides and top of the panel to the sides and top of a frame 12 which projects outwardly from and surrounds the opening 2 is a casing 13. Another similar strip 14 of the casing material but independent of the casing 13 extends from the bottom of the frame 12 to the adjacent end of the base 3, said strip being the full width of the frame and base. The casing members are both of flexible air-tight and fire-proof fabric of suitable character. The casing 13 is securely but detachably connected to the sides and top of the frame and panel, and also along the sides of the base by suitable means such as pins 15 on the rigid members engaging eyelets 16 in the casing. These members may be of a nature such as is commonly used in connection with the side curtains of motor vehicles and the like.

The casing member 14 may be secured to the base and frame in the same manner or permanently if desired.

Between the base and the furnace the sides of the casing 13 have longitudinal flaps 17 along the bottom to fold under the side edges of the member 14, being detachably connected thereby by a pin and eye arrangement therebetween such as that above described.

It is to be understood that not only are the casing members of air-tight material, but the upper face of the base also is non-perforated so as to be air-tight as well.

It will therefore be seen that an air-tight enclosure of vibrationless character surrounds the opening 2 and encloses the parts on the base, so that air for the burner can only pass through the panel opening 10. Since this panel is beyond the motor and other parts, the opening 10 is unobstructed throughout and the volume of air passing therethrough may therefore be accurately controlled by manipulation of the door 11.

The main casing 13 being detachably mounted it may be easily folded back one

way or the other or removed when desired to get at the parts mounted on the base. 60

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims. 70

Having thus described my invention what I claim as new and useful and desire to secure by Letters Patent is:

1. An oil burner installation for a firebox having a side opening therein comprising a base rigidly mounted outside the firebox, a rigid extension integral with the base projecting through the opening into the firebox in spaced relation to the sides and bottom of the opening, an oil burner supported by the extension at its inner end, and operating means for the burner mounted on the base. 75

2. An oil burner installation for a firebox having a side opening therein comprising a base rigidly mounted outside the firebox, a rigid extension from the base projecting through the opening into the firebox in spaced relation to the sides and bottom of the opening, an oil burner supported by the extension at its inner end, operating 80 means for the burner mounted on the base, and a casing of vibrationless material enclosing said operating means and surrounding the firebox opening and attached to the furnace around said opening. 95

3. In connection with a firebox having a side opening therein and an oil burner in the firebox, a base fixed outside the firebox, operating means for the burner mounted on the base, a panel projecting upwardly from the outer end of the base, a horizontal member extending between the bottom of the firebox opening and the adjacent end of the base, said member being the same width as the opening and base, and a flexible casing 100 passing about and attached to the sides and top of the panel and extending thence to the sides and top of the firebox opening, detachable connections between the firebox and casing, side flaps on the casing to engage the side edges of the horizontal member, and detachable connections between said flaps and member. 105

In testimony whereof I affix my signature.

IRA E. SMITH.
